(57) CLAIM

The ornamental design for a hair removal device, as shown and described.

DESCRIPTION

FIG. 1 is a front, top and right side perspective view of a hair removal device, showing my new design;

FIG. 2 is a rear, top and right side perspective view thereof;

FIG. 3 is a front, bottom and right side perspective view thereof;

FIG. 4 is a front, bottom and left side perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is an enlarged view of portion "11" shown in FIG. 4.

The dash-dot-dash broken lines illustrate enlarged view indicators and form no part of the claimed design.
